FLUE CONNECTOR ASSEMBLY FOR
ABSORPTION REFRIGERATORS

Clifford D. Pfender, Albert Schultze, and Carl J.
Knerr, Evansville, Ind., assignors to Servel, Inc.,
New York, N. Y., a corporation of Delaware

Application July 15, 1947, Serial No. 761,016

5 Claims. (Cl. 62—1)

1

This invention relates to refrigeration and particularly to heat operated refrigerating systems wherein a generator or vapor expeller is heated by a liquid fuel burner.

It is an object of this invention to provide a connector between a refrigerating apparatus and its heater that is actuated by movement of the heater to and from its operative position when servicing.

The invention together with the above and other objects and advantages will be more clearly understood from the following description and accompanying drawing, wherein:

Fig. 1 is a side view partially in vertical section, of the lower portion of a refrigerator embodying this invention;

Fig. 2 is a view similar to Fig. 1, showing certain of the parts in different relative positions;

Fig. 3 is a view similar to Fig. 1, showing the parts in still different relative positions; and

Fig. 4 is a horizontal sectional view, taken substantially on line 4—4 of Fig. 3.

Referring now to the drawing, particularly to Fig. 1, reference character 10 denotes a refrigerator cabinet provided with a food storage compartment 11 and a mechanism compartment 12 beneath the food storage compartment. The food storage compartment is cooled by an absorption refrigerating system, only the generator 13 of which is shown. This generator includes a cylindrical shell 14 having a concentric flue 15 projecting therethrough. The generator is encased in an insulation box 16 having a suitable insulating material 17 therein. As shown, the lower end of the generator flue projects beyond the bottom of the insulation box. A liquid fuel tank 18, containing a suitable fuel such as kerosene, is movably mounted in the mechanism compartment, as by rollers 19 on each side of the fuel tank, which rollers are adapted to travel in guideways 20 at each side of the tank. A heater comprising a burner 21 is mounted in any suitable manner upon the fuel tank and is provided with a wick, not shown, but which wick projects into the fuel tank. An adjusting member 22, having an extension 23, is provided for raising and lowering the burner wick. A knob 24 is provided on the outer end of extension 23, so that the burner wick may be adjusted from the lower front portion of the refrigerator. A handle 25 is provided on a front portion of the fuel tank for moving the tank into and out of mechanism compartment 12. Burner 21 is provided with a stub chimney 26 made of glass or other suitable transparent material, so that the

2

burner flame may be viewed from the lower front of the refrigerator.

To provide for good heating efficiency, it is desirable that the burner and the bottom of the generator flue 15 be connected when the burner is in operative position beneath the generator flue. It is also desirable that the burner be free to move relative to the generator flue, so that the burner may be serviced from time to time. In accordance with this invention, a sealing ring 27, made of metal or other suitable heat resisting material and provided with a central opening 28 therein, is slidably mounted upon the lower projecting end of the generator flue 15. The lower surface of ring 27 is ground smooth, as is the upper surface of stub chimney 26, so that when the ring rests upon the chimney, as shown in Fig. 3, a good seal is made between these two elements.

An operating mechanism, indicated generally by reference character 29, is provided for raising and lowering the ring 27 relative to the lower end of the flue and to the stub chimney. Operating mechanism 29 includes a bifurcated lever arm 30 having a pair of fingers or prongs 31 adapted to engage the lower portion of ring 27 on two sides thereof, as best shown in Fig. 4. The lever arm 30 is rotatably mounted on a horizontal shaft 32, which shaft is mounted upon two brackets 33, and which brackets, in turn, are secured, as by spot welding or the like, to the bottom portion of insulation box 16. A lever arm 34 is attached to and projects downward from the center rear portion of bifurcated member 30 forming therewith a bellcrank. The arm 34 has a horizontal end portion 34a arranged to be contacted by the body portion of the burner 21 as said burner is moved to a position beneath the generator flue 15. A torsion spring 35, wound around the shaft 32, is arranged to bias the bellcrank clockwise and thus toward the upper position of the fingers 31 as shown in Figs. 1 and 2. A stop member 36 is provided for limiting the inward movement of the fuel tank so that lever 34 is not appreciably distorted by contact with the burner 21.

In operation, when it is desired to service the burner 21, fuel tank 18 is moved from the position shown in Fig. 3 to that shown in Fig. 2. As the tank is moved outward from the mechanism compartment, the burner 21 moves away from the lever arm 34 so that the torsion spring 35 rotates the fingers 31 of the bifurcated member upward, whereupon the ring 27 is moved from the position shown in Fig. 3 to that shown in Fig. 2, and a suitable clearance is provided between the chim-

ney 26 and the ring member, so that the fuel tank and attached burner and chimney may be moved out of the mechanism compartment. After the burner has been serviced the fuel tank is returned to the mechanism compartment, with the rollers 19 guided in guides 20, the tank is moved toward the rear of the mechanism compartment. As the tank and attached burner approaches the position shown in Fig. 2, the burner contacts the horizontal end portion 34a of lever 34 and continued movement of the tank and attached burner toward the rear of the mechanism compartment causes the prongs 31 of the bifurcated member to be rotated downward, whereupon the ring 27 is lowered to the position shown in Fig. 3 and a seal between the chimney and lower end of the generator flue is again effected. The stop member 38 limits the inward movement of the fuel tank. As shown best in Fig. 3, when the fuel tank, burner and chimney are in their final operative position relative to the lower portion of the generator flue, the ends of the prongs 31 are clear of the ring member 27, so that the ring member rests by force of gravity upon the upper portion of the stub chimney, whereby a sealed flame path between the burner and the lower end of the generator flue is assured.

Having thus disclosed our invention, we wish it understood that we do not desire to be limited to the specific structure illustrated and described, for obvious modifications thereof may occur to a person skilled in the art.

What is claimed is:

1. In a refrigerator having a heat-receiving element provided with a flue, a heater for said element having a chimney and removably mounted in an operative position with an end of said chimney adjacent an end of said flue, a member co-acting with said flue and chimney and movable

relative to both the flue and the chimney to and from a position connecting the adjacent ends of the flue and the chimney, and mechanism to move said member and operative responsive to movement of said heater to and from said operative position.

2. A refrigerator as set forth in claim 1 in which said member is a ring slidable up and down on the end of the flue and adapted to rest upon the end of the chimney when the heater is in said operative position, and said mechanism includes a lever arm having a pair of prongs adapted to engage beneath opposite sides of said ring for lifting same.

15 3. A refrigerator as set forth in claim 2 in which said lever arm is biased in the ring-raising direction and operable to lower the ring and move clear thereof when the ring rests on the chimney.

4. A refrigerator as set forth in claim 1 in which 20 said mechanism comprises a bellcrank having one arm adapted to engage said connecting member, and the other arm adapted to be operated by movement of said heater.

5. A refrigerator as set forth in claim 1 in which 25 said member is a ring slidable up and down on the flue and adapted to rest on the chimney, and said mechanism comprises a bellcrank having a bifurcated lever arm adapted to engage beneath said ring on opposite sides thereof, and the other arm adapted to be operated by movement of said heater, and means for biasing the bellcrank in a direction to cause upward movement of said bifurcated lever arm.
